HAIRPIN

Frank G. Hall, Chicago, Ill.

Application January 26, 1953, Serial No. 23,292

Term of patent 3½ years

(Cl. D86—10)

To all whom it may concern:

Be it known that I, Frank G. Hall, a citizen of the United States, residing at Chicago, State of Illinois, have invented a new, original, and ornamental Design for a Hairpin, of which the following is a specification, reference being had to the accompanying drawing, forming a part hereof.

Figure 1 is a top plan view of a hairpin, showing my new design;

Figure 2 is a side elevation of a hairpin, showing my new design;

Figure 3 is a bottom plan view of a hairpin, showing my new design;

Figure 4 is an end elevation of a hairpin, showing my new design; and

Figure 5 is an enlarged sectional view of a hairpin, taken on line 5—5 of Figure 2.

I claim:

The ornamental design for a hairpin, as shown.

FRANK G. HALL.
